United States Patent

Des. 237,703
Patented Nov. 18, 1975

237,703

WHEEL CENTER

Richard Harold Clement and Donald Gene Melbinger,
La Grange, Ill., assignors to Clement Wheel Company,
Inc., Chicago, Ill.

Filed Mar. 3, 1975, Ser. No. 554,729

Term of patent 14 years

Int. Cl. D12—16

U.S. Cl. D12—211

FIG.1

FIG. 2

FIG. 3

FIG. 4

FIG. 5

FIG. 1 is a top plan view of a wheel center showing our new design;

FIG. 2 is a side elevational view thereof;

FIG. 3 is a fragmentary sectional view thereof, taken along line 3—3 in FIG. 1;

FIG. 4 is a top plan view of a wheel center showing a second embodiment of our new design, wherein the sole difference resides in the deletion of two bolt holes; and

FIG. 5 is a top plan view of a wheel center showing a third embodiment of our new design, wherein the sole difference resides in the deletion of three bolt holes.

We claim:

The ornamental design for a wheel center, as shown.
